WITNESS:

P. R. Michel.

UNITED STATES PATENT OFFICE.

CHESTER W. LARNER, OF PHILADELPHIA, PENNSYLVANIA, ASSIGNOR, BY MESNE ASSIGNMENTS, TO I. P. MORRIS CORPORATION, A CORPORATION OF DELAWARE.

DOUBLE-PLUNGER VALVE.

Application filed May 6, 1921. Serial No. 467,417.

The nature and objects of the present invention will appear from the following description which will be made with reference to the accompanying drawings forming part 5 hereof and in which

Figure 1 is a view principally in section.

Fig. 2 is a view principally in section showing a modification, and

Fig. 3 is a detached sectional view of a 10 detail.

This invention consists of a double plunger valve adapted to operate under conditions of flow in either direction. Fig. 1 shows one embodiment having a body or casing 1 contracted at both ends with radial ribs 2 integral with the casing 1 and bored out to support in proper position an internal cylinder 3 having a partition or bulkhead 4 separating the space within the cylinder 3 20 into two chambers 5 and 6.

The internal cylinder 3 contains plungers 7 and 8 sliding within it and closing against seats 9 and 10 at each end of the body 1 to stop the flow through the body. Plunger 7 closes against seat 9 to stop flow from right to left in the figure and plunger 8 closes against seat 10 to stop the flow in the opposite direction. Plungers 7 and 8 are rigidly connected together by a hollow strut 11 25 attached to each plunger by nose pieces 12. Strut 11 has a central bore which contains rod 13 and has a recess at the center in which a rack 14 slides longitudinally.

The nose pieces 12 are provided with 30 apertures 15 for the purpose of discharging pressure from chambers 5 and 6 into the conduit and the discharge of pressure through these apertures is controlled by the motion of rod 13 which may be utilized to open or close either of these apertures according to the direction in which it is moved. Rack 14 is rigidly connected to rod 13 by pins 16 or by other suitable means. A pinion 17 engages rack 14 and moves it in 35 either direction according to whether it is desired to close plunger 7 or plunger 8. Pinion 17 is mounted on a shaft 18 which passes through cylinder 3 and body 1 and is operated by suitable mechanism from the 40 outside of the valve.

When there is flow or tendency to flow in the conduit plungers 7 and 8 are opened and closed in the manner described in my

Patent No. 1,465,916 and which may be very briefly described as follows: Plunger 7 can 55 be operated solely by pressure and in such a way as to follow the movement of the adjacent end of the rod 13 by differentiating the pressure in the chamber 5, provided past the plunger 8 and through the fluid way between the body and cylinder and thence by the clearance between the plunger 7 and cylinder, with the pressure on the outside of the nose of the plunger 7, the operation of the plunger 8 being the same. When the conduit is empty or there is no tendency to flow, however, the operation is slightly different. Plunger 7 is then closed by moving rod 13 to the left, the end of rod 13 abutting against its seat at aperture 15, and is opened by reversing the movement of rod 13 until the other end of the rod abuts against the seat at aperture 15 in plunger 8. The operation of plunger 8 is the reverse of the operation of plunger 7. 75

When flow or tendency to flow is from right to left in the drawing it is controlled by the operation of plunger 7, pressure being exhausted from or retained in chamber 5 which is separated from chamber 6 by partition 4 which fits closely around strut 11 in order to prevent excessive leakage between chambers 5 and 6. When plunger 7 is being operated plunger 8 is inert and vice versa. 85

Figure 2 shows another embodiment of this invention in which plungers 7 and 8 are not rigidly connected together as in Fig. 1. In this case when one plunger is closed the other is also closed and when one is open the other is also open. The principle of using the lefthand plunger to control flow from right to left and the righthand plunger to control flow from left to right, however, is retained. Pinion 17 engages two racks 14^a connected to rods 13^a which operate plungers 7 and 8 in the manner described in copending application, Serial No. 294,155. In this case the rods 13^a have enlarged ends 19 which are utilized to pull plungers 7 and 8 open by abutting against bearings 20 connected to the plungers, whenever there is no flow or tendency to flow in the conduit. 90 95 100 105

It is clear that if, for example, flow is occurring from right to left in the figure and plunger 7 is closed under these conditions it

will be held tightly to its seat by pressure in chamber 5 admitted through the clearance between plunger 7 and cylinder 3. At the same time, although plunger 8 is closed it is not held against its seat by difference of pressure but merely by the pressure of 19 against the seat of aperture 15. This pressure, particularly in view of the unavoidable lost motion in the gearing, is not sufficient to prevent leakage past the seat of plunger 8 and this leakage maintains pressure inside of body 1 and in chamber 5 to hold plunger 7 tightly closed.

The same is true when plunger 8 is closed if the source of pressure is in the conduit to the left of the valve.

The partition 4 of Fig. 2 may in some cases be omitted. Assuming then, for example, that the plungers are closed to stop flow from right to left and it is desired to open the valve, pinion 17 is rotated clockwise, drawing rods 13^a toward the center of the valve. This opens aperture 15 in plunger 7, dropping the pressure inside of both plungers. Plunger 7 is unseated and opens as fast as the rod 13^a is withdrawn, due to a preponderance of pressure on the outside of the plunger. Plunger 8 is also unseated and opens as fast as its rod 13^a is withdrawn, but in this case the entire outside surface of the plunger nose is subjected to full pressure and owing to the reduction of pressure inside the plunger, the plunger is pressed against the end 19 of rod 13^a which alone restrains the movement of the plunger. This throws a heavy strain upon the racks 14^a and the pinion 17 and its operating mechanism. For this reason it is advisable to use the partition 4 excepting possibly in the case of small valves.

Fig. 3 shows a modification in that portion of body 1 and plungers 7 and 8 adjacent to the plunger seat which is under certain circumstances advantageous.

Under some conditions and particularly when these valves are used with gases instead of liquids there may be some tendency toward uneven or erratic movement of the plunger as it approaches the closed position and is subjected to sudden changes of pressure on the exposed area of the plunger which lies within the seat. This in the case of gas valves is due to the elasticity of the gas and the fact that the plunger will move as a result of the expansion or contraction of the gas before sufficient time has elapsed to permit sufficient flow to take place through aperture 15 to equalize the pressures inside and outside of the plunger.

In Fig. 3 a shoulder 21 is provided inside body 1 adjacent to the seat and a corresponding recess 22 is provided in the plunger. The cylindrical surface of recess 22 fits into the cylindrical surface of shoulder 21 with a small clearance and thus practically stops

the flow through the valve before plunger 8 reaches its seat and the additional movement of the plunger thus provided after flow ceases and before the plunger seats is sufficient to enable aperture 15 to equalize the pressures inside and outside of the plunger and prevent the plunger seating with undue violence.

It will be obvious to those skilled in the art to which the invention relates that modifications may be made in details of construction and procedure without departing from the spirit thereof which is not limited as to those matters or otherwise than as the prior art and the appended claims may require.

I claim:

1. A double plunger valve operative with flow in either direction and comprising in combination a body contracted at each end and having plunger seats and provided with an internal cylinder spaced from it to provide a fluid way, two plunger chambers separated by a bulkhead or partition provided in the cylinder, two plungers co-operating with the chambers and seats and past one of which pressure is available in the fluid way and in the chamber of the other, and valved apertures through the plungers for differentiating said pressure in the chamber from the pressure on the outside of the corresponding plunger to operate the latter.

2. A double plunger valve operative with flow in either direction and comprising in combination a body contracted at each end and having plunger seats and provided with an internal cylinder spaced from it to provide a fluid way, two plunger chambers separated by a bulkhead or partition provided in the cylinder, two plungers co-operating with the chambers and seats and past one of which pressure is available in the fluid way and in the chamber of the other, valved apertures through the plungers for differentiating said pressure in the chamber from the pressure on the outside of the corresponding plunger to operate the latter by fluid pressure, and mechanical means accessible from the outside of the body and connected with the plungers and adapted to operate them in the absence of fluid pressure sufficient to move the plungers.

3. A double plunger valve operative with flow in either direction and comprising in combination a body contracted at each end and having plunger seats and provided with an internal cylinder spaced from it to provide a fluid way, two plunger chambers separated by a bulkhead or partition provided in the cylinder, two plungers co-operating with the chambers and seats and past one of which pressure is available in the fluid way and in the chamber of the other, valved apertures through the plungers for differentiating said pressure in the chamber from the pressure on the outside of the corresponding plunger to operate the latter, a

strut for holding the plungers in spaced relation, and a rod carrying the aperture valves and connected with the strut for limited movement in respect thereto.

5. 4. In combination, a conduit having a portion tapering inwardly in the direction of flow, a hollow valve plunger, means co-operating therewith to form a fluid pressure operating chamber therefor, a valve seat and 10 a shoulder on said tapering portion comprising a substantially cylindrical surface projecting from said seat toward the valve plunger, said hollow valve plunger being provided with a cylindrical surface adapted 15 to fit in the cylindrical portion of said shoulder and also having a connection from its interior to the fluid-way below said seat, whereby said plunger in cooperation with the tapering portion of said conduit is adapted 20 to gradually cut off fluid-flow through said conduit and thereafter being adapted to move the length of said cylindrical recess before said seat is engaged, and said interior connection, during movement of the plunger 25 through said cylindrical recess, being adapted to permit communication between said chamber and the fluid-way below said seat, thereby to reduce the operating fluid pressure in said chamber and permit a gradual 30 retardation of the plunger so that said seat is engaged relatively easily.

5. A double plunger valve adapted to stop and to regulate flow in either direction having in combination means comprising adjustable apertures through the plungers to automatically balance the fluid pressures acting on the plungers to hold them stationary at any desired position or to unbalance said fluid pressures to move said plungers, and 40 mechanical means to move said plungers when said fluid pressure means are insufficient.

6. A double plunger valve operative with flow in either direction and comprising in combination a body contracted at each end and having plunger seats and provided with an internal cylinder spaced from it to provide a fluid way, two plunger chambers separated by a bulkhead or partition provided 50 in the cylinder, two plungers co-operating with the chambers and seats and past one of which pressure is available in the fluid way and in the chamber of the other, valved apertures for differentiating said pressure 55 in the chamber from the pressure on the outside of the corresponding plunger to operate the latter, and means for holding the plungers in spaced relation.

7. The combination with a conduit casing 60 having oppositely disposed valve seats, of a stationary cylindrical housing spaced from said casing to form a fluid way therebetween, oppositely directed movable valve plungers slidably supported by said housing and adapted to engage said seats, fluid 65

pressure operated means within said housing for moving said plungers in unison with each other in the same direction so that when one plunger closes the other opens.

8. The combination with a conduit casing 70 having oppositely disposed valve seats, of a stationary cylindrical housing having oppositely directed movable valve plungers adapted to engage said seats, and mechanical means having controlling means movable 75 relative to said plungers while disposed within said housing for moving said plungers in unison with each other in the same direction so that when one plunger opens the other plunger closes.

9. The combination with a conduit casing having oppositely disposed valve seats, of a stationary cylindrical housing spaced from said casing to form a fluid way therebetween, oppositely directed movable valve 85 plungers slidably supported by said housing and adapted to engage said seats and combined mechanical and fluid pressure means within said housing for moving said plungers in unison with each other, in 90 the same direction so that when one plunger closes the other opens.

10. The combination with a conduit casing having oppositely directed valve seats of a stationary cylindrical housing between 95 said seats, movable valve plungers sliding in said housing and seating against said seats, and fluid pressure operated means for moving said valve plungers comprising means for balancing the pressures on opposite sides 100 of one of said plungers and simultaneously unbalancing the pressures on the other of said plungers.

11. The combination with a conduit casing having oppositely directed valve seats of a stationary cylindrical housing between 105 said seats, movable valve plungers sliding in said housing and seating against said seats, and fluid pressure operated means for moving said valve plungers comprising means for balancing the pressures on opposite sides 110 of one of said plungers and simultaneously unbalancing the pressures on the other of said plungers and means connecting said valve plungers to move in unison.

12. The combination with a conduit casing having oppositely disposed valve seats, of a cylindrical housing for containing fluid pressure, oppositely directed valve plungers adapted to engage said seats and movably supported by said housing, and means adapted to move with said plungers for controlling the discharge of fluid contained in said housing whereby movement of said plungers may be controlled in either direction.

13. The combination with a conduit casing having oppositely disposed valve seats, of a stationary cylindrical fluid containing housing having oppositely directed valve means, movably supported thereby and adapted to 130

engage said seats, and means adapted to move with said plungers for controlling the fluid pressure within said housing, whereby the movable valve means may be controlled 5 in either direction.

14. The combination with a conduit casting having oppositely disposed valve seats, of a stationary cylindrical fluid containing housing having oppositely directed valve 10 means, movably supported thereby and adapted to engage said seats, and means for moving said valve means in opposite directions by fluid pressure, including an element adapted to move with said valve means 15 and common to the control of said fluid in either direction of said movements.

15. The combination with a conduit casting having oppositely disposed valve seats, of a stationary supporting member, oppositely directed hollow valve plungers movably supported by said stationary member and adapted to engage said seats, means whereby fluid pressure is admitted to the hollow portion of said plungers to move the 25 same in opposite directions, said latter means including valve means for controlling the fluid pressure in said hollow plungers, and mechanical actuating means extending laterally from said plungers and intermediate their ends for controlling the fluid 30 therein.

16. The combination with a conduit casting having oppositely disposed valve seats, of oppositely directed ported hollow valve 35 plungers adapted to engage said seats, and means for controlling the ports of each of

the oppositely directed plungers whereby plunger movement may be controlled.

17. The combination with a conduit casting having oppositely disposed valve seats, of a stationary central member, oppositely directed ported hollow valve plungers movably supported thereby and adapted to engage said seats, means whereby fluid pressure may be admitted to said hollow plungers, and means for controlling the ports of each of the oppositely directed plungers whereby plunger movement may be controlled. 45

18. The combination with a conduit casting having oppositely disposed valve seats, of a stationary central supporting member, oppositely directed hollow ported valve plungers movably supported by said central member and adapted to engage said seats, 55 the ports of said plungers extending in opposite directions, and movable means for opening or closing said ports whereby when a port is closed plunger movement will occur in the direction which said port closing 60 means moves.

19. The combination with a conduit casting having oppositely disposed valve seats, of a stationary central supporting member, oppositely directed hollow movable valve 65 plungers adapted to engage said seats, said plungers having ports extending in opposite directions, and movable means for closing said ports, whereby plunger movement is effected in the direction of movement of 70 the port closing means.

CHESTER W. LARNER.
